Inventor:
Donald E. Necas,
By Holgren, Wegner, Allen,
Stibman & McCord Atty's.

FIG. 1 is a perspective view of a refuse compactor cabinet and drawer structure, embodying the invention adapted for use with any one of a plurality of different control panel;

FIG. 2 is a right-hand side elevation thereof, the left-hand view being reversely similar;

FIG. 3 is a top plan view thereof;

FIG. 4 is a rear view thereof;

FIG. 5 is a perspective view of the refuse compactor cabinet and drawer structure embodying the design having one specific control panel design installed therein;

FIG. 6 is a fragmentary enlarged front view thereof illustrating in greater detail the control panel of the species design of FIG. 5;

FIG. 7 is a side elevation taken substantially along the line 7—7 of FIG. 6; and

FIG. 8 is a vertical section taken substantially along the line 8—8 of FIG. 6 to illustrate more clearly the configuration of the control panel of FIG. 5.

I claim:

The ornamental design for a refuse compactor cabinet and drawer structure, as shown and described.
